UNITED STATES PATENT OFFICE.

SEBASTIAN ZIANI DE FERRANTI, OF LONDON, ENGLAND.

STEAM-TURBINE.

No. 892,818.

Specification of Letters Patent.

Patented July 7, 1908.

Application filed October 31, 1903. Serial No. 179,407.

To all whom it may concern:

Be it known that I, SEBASTIAN ZIANI DE FERRANTI, a subject of the King of Great Britain and Ireland, and resident of 31 Lyndhurst road, Hampstead, London, N. W., England, have invented certain new and useful Improvements in Steam-Turbines, (for which I have made application for Letters Patent in Great Britain, No. 24,781, bearing date November 11, 1902, and No. 7,685, bearing date April 2, 1903; in Germany, bearing date May 29, 1903, and in Austria-Hungary, bearing date April 21, 1903,) of which the following is a specification.

15 My invention relates to turbine heat engines employing the expansion of a comparatively readily condensable elastic fluid, such as steam, ether, oil vapor, ammonia or the like. I have found by calculation and experiment that in such elastic fluid turbine engines, utilizing the expansion of the elastic fluid, a very great gain in the total efficiency takes place if, after superheating, the expansion be caused to take place isothermally instead of adiabatically, as is the usual practice. I find also that there is some gain in the total efficiency if the fluid is expanded isothermally instead of adiabatically without initial superheat. I believe the gain due to 25 the isothermal instead of adiabatic expansion in the two cases mentioned is to be attributed partly to thermo-dynamic and partly to mechanical causes, though the proportional gain due to each cause probably 30 differs greatly in the two cases, as will be explained hereafter.

It is well known that in elastic fluid heat engines, turbine or otherwise, 1 lb. of the fluid vapor need only take away a quantity 40 of heat to the condenser equal to H_2 , the latent heat of the fluid at the pressure of exhaust. Most engines throw away to the condenser an amount, per pound of fluid, less than this, depending on the wetness of the fluid at the end of expansion. In an engine 45 free from external cooling and with the usual limits of pressure, the amount varies between 85% and 90% of this. In engines or turbines not expanding down to the pressure of the 50 condenser or of the atmosphere into which they exhaust, a feed heater or regenerator must be used to reduce the loss to a minimum. Such a regenerator takes R units of heat per pound of fluid from the exhaust and transfers 55 them to the feed of the generator or boiler.

As an approximation in the case of known engines we may take it that H_2 units are thrown away to the condenser per pound of fluid and if H_1 is the heat given to the pound of fluid initially by the fuel, then $H_1 - H_2$ is 60 the amount of heat turned into work, and $\frac{H_1 - H_2}{H_1}$ the efficiency of the engine or turbine so that $H_1 = H - R$ units, where H is the total heat received by the fluid per cycle. 65

For a given exhaust pressure, H_2 is fixed, and the thermal efficiency can only be increased by making H_1 greater. This may be done by increasing the pressure of the fluid vapor, and the practical limit in this direction has probably been reached. It requires a very great increase in the pressure to increase H_1 even by a small amount. Another way is to heat the fluid vapor out of contact with its liquid without increasing its pressure, that is, to superheat it. Here again, the practical limit is soon reached, since the materials we can use will not stand a much higher temperature than 400° C. Superheating up to 400° C., does not increase the 80 value of H_1 very much.

Now my invention relates to a method of increasing H_1 very greatly without passing beyond the practical limits of temperature and pressure. The principle which it approximates is that of adding enough heat during the expansion of the fluid to keep its temperature constant; this is called isothermal expansion. In this case, however, 1 lb. of fluid at the end of expansion is superheated and contains more than H_2 units of heat; but this can be reduced to H_2 units by the use of a regenerator which transfers some heat to the working fluid. The way in which I approximately realize 95 isothermal expansion is to expand the fluid vapor in several stages in a turbine or engine, reheating the fluid vapor between some or all of the stages in reheaters up to the initial temperature of the vapor. The vapor 100 after the last expansion passes into a regenerator preferably of counter flow type to heat the feed till it (the vapor) loses as much heat as possible. On leaving the regenerator the fluid is exhausted as desired into a 105 condenser or the atmosphere. The greater the number of stages in which the fluid vapor is reheated, the more nearly does its temperature keep to a high constant value and the more nearly is isothermal expansion 110

realized; the greater also is the quantity of heat turned into work, per unit of working fluid.

If the fluid is superheated before isothermal expansion, it in this way takes in a large quantity of heat at the highest temperature and consequently there is a large increase in the thermodynamic efficiency compared with the case of superheated steam expanding adiabatically. Isothermal expansion of the superheated fluid also has the advantage of entirely preventing condensation within the turbine, while with adiabatic expansion it is, in ordinary cases, impracticable to superheat the fluid sufficiently to prevent condensation towards the end of the expansion. Thus, in turbines of the Curtis type expanding steam successively through several nozzles, even though the steam be initially superheated to as high a temperature as is practicable, it will begin to get wet before traveling more than a comparatively short distance through the turbine and will get wetter and wetter until exhausted. This condensed vapor largely increases the friction of the turbine wheels revolving in it and absorbs considerable power; so that isothermal expansion, apart from the thermodynamic gain over adiabatic expansion pointed out above, also gives rise to a mechanical gain due to the lessened friction. If the fluid is not superheated before expansion, the thermodynamic gain of isothermal over adiabatic expansion is probably small, as the temperature at which heat is taken in during the expansion is but little higher than the average temperature of feed-heating and evaporation and consequently this heat is not capable of being converted into work with any greatly increased efficiency. The indirect mechanical advantages due to the prevention of condensation are however greater in this case, as without superheating the fluid is wet throughout if adiabatic expansion is employed. Therefore, either with or without initial superheat, the employment of isothermal instead of adiabatic expansion gives rise to a large increase in the total efficiency.

My invention therefore consists broadly in reheating the elastic fluid employed in a multiple expansion turbine engine between the various stages of expansion in such a way that the total expansion more or less closely approximates to true isothermal expansion, whereby an amount of heat greatly in excess of the whole of the available heat contained initially in the elastic fluid used may be added and efficiently utilized and a great increase in economy attained.

My invention further consists: (1) in employing a regenerator in conjunction with an isothermal expansion turbine engine to extract and utilize the heat from the outflowing

thermal expansion engines with superheaters, re-heaters, boilers, regenerators and water-heaters, whereby economical utilization of fuel may be obtained; and (3) in arranging the elements which form the complete power generator employing practically isothermal expansion, all in one machine, combined so as to save heat loss. It will be seen that an isothermal expansion power generator, according to my invention, may be constructed of a greater or less number of elements, according to the degree of increased economy which is aimed at.

Referring to the accompanying drawings:—Figure 1 shows the general arrangement in elevation of a complete installation of plant having fire-heated superheaters and re-heaters, Figs. 2, 3 and 4 being corresponding sections on the lines XX, YY and ZZ respectively of Fig. 1. Fig. 5 shows a modification of the arrangement of Fig. 1 and Fig. 6 an arrangement adapted to the case of a Lancashire or other flue boiler. Fig. 7 shows another general arrangement in which superheated steam is employed in the re-heaters; Fig. 8 is a detail view showing an alternative arrangement of the re-heater coils; Fig. 9 is a modification of the arrangement of the re-heaters of Fig. 7, while Figs. 10 and 11 show diagrammatically other methods of reheating by means of superheated steam. Fig. 12 shows a longitudinal section of the turbine as a whole.

I will describe my invention as applied in one modification in what I consider its best form, viz., with all the elements combined together in one machine so as to obtain the highest economy. I will assume the turbine is to use steam as the medium of expansion and that it is desired to employ a compound turbine of the impact type, although it will be seen that any condensable elastic fluid may be used and that a compound turbine of any of the other well-known types may be employed. I therefore construct (Figs. 1 to 4) a compound or multiple stage impact steam turbine, *a*, in a well known manner but I separate each stage in such a way that I can pass the steam exhausting from the first stage through a re-heater delivering into the inlet of the second stage and from its exhaust to a second re-heater and so on, re-heating after each stage expansion to the final exhaust. I arrange the turbine, *a*, on a horizontal shaft and provide the re-heaters below the turbine body. These re-heaters, *b*, *c*, are tube elements situated in a combustion flue, *d*, which also contains the boiler, *e*, *f*, superheater, *h*, *i*, and water heater, *k*, *l*, elements.

In connection with the exhaust passage, *m*, of the turbine, I arrange a coil regenerator, *n*, so as to extract the heat from the exhaust which comes from the turbine at a temperature approaching the maximum tem-

perature of the cycle; I arrange the water supply to the inlet of this regenerator to come from the condenser, *u*, or from the hot well by way of the pipe, *o*, and I connect the regenerator outlet, *p*, which is nearest to the turbine, preferably to the water heater element, by way of the pipe, *r*, so that the heat of the turbine exhaust is in part restored to the working fluid.

10 I find it convenient to employ boiler, *e*, *f*, and superheater elements, *h*, *i*, of a similar character, which may take the form of upper and lower drums, joined by a large number of nearly vertical tubes, which traverse the 15 flue, *d*, and therefore baffle the combustion gases. The boiler, superheater, re heater and water heater elements are all arranged in the flue, *d*, in such a way as to obtain the best extraction of heat from the gases of combustion, 20 which are produced and burned from one end of the furnace. I may also employ coal-dust as the furnace combustible.

Beneath or around the furnace flue, carrying the boiler, superheater, re heater and 25 water heater elements; I prefer to construct flues to carry the products of combustion to the chimney, *s*, and through these waste gas flues I carry iron air ducts, *t*, which convey the air supply to the furnace in a direction 30 preferably counter to the flow of the waste gases, thus forming an air regenerator and obtaining hot air for the fuel combustion.

According to a modification, as shown in Fig. 5, the length of piping between the turbine and re heaters is reduced to a minimum, the regenerator being removed from the position shown in Fig. 1 and placed beyond the flue heated elements. Fig. 5 also shows another form of re heater consisting in one or 40 more heaters from which tubes depend. Fig. 6 shows an arrangement of parts in which a Lancashire or other flue boiler is used instead of the water tube boilers of Fig. 1.

The same letters are used in the last two 45 figures as in Fig. 1 to denote similar parts.

According to another modification shown in Figs. 7, 8 and 9, instead of direct fire-heating of the re heaters, I arrange them to be heated indirectly by superheated steam. 50 Thus in Fig. 7, the steam generator is shown at 2, provided with steam drums, 3, from which the steam is led through the superheater, 4, in the uptake. After superheating, the steam divides into two parts, one part 55 going direct to the turbine, 5, by way of the pipe, 6, and the other part passing to the re heaters, 7, by way of the pipe, 8. In the example shown the turbine is provided with five re heaters, the superheated steam from 60 the pipe, 8, passing through them in parallel.

A pump, 9, is provided to return the 65 condensed steam issuing through the pipe, 25, from the re heaters to the boiler through the pipe, 10, feed water heater, 26, and pipe, 27.

65 The arrangement I prefer in the re heaters is

to conduct the steam from the turbine after the first stage of expansion through the pipe, 11, to the bottom of the first re-heater and then upwards in a direction counter to that of the superheated steam through the coil, 12, and back to the turbine. This action is 70 repeated after each stage of expansion in the turbine, the steam finally passing through the exhaust pipe, 13, to the regenerator, 14. It will be understood that as the figure is 75 merely diagrammatic, the proportions of re-heater coils and the other parts are not those which would be adopted in practice. An alternative arrangement of the re-heater coils is shown in Fig. 8, steam from the turbine being led to the bottom of the re-heater through the pipe, 15, whence it returns through the pipe, 16, meanwhile traveling in an opposite direction to that of the superheated steam which enters the top of the re-heater through 80 the pipe, 17, and flows through the coil, 18, to its outlet, after which its path back to the 85 boiler is as before.

Referring again to Fig. 7, the steam from the turbine passes through the regenerator 90 to the condenser, 19, which may be of the jet condensing type, supplied with cooling water through the pipe, 20, and provided with an air pump, 21. Another pump, 22, which may if convenient, be worked off the air 95 pump, 21, serves to pass a part of the outflow from the condenser through the regenerator coils, 28, whence it passes on and joins the 100 condensed steam from the re-heaters. The combined steam may then be pumped through the economizer or feed-water heater, 100 placed in the uptake and returned to the boiler, thus completing the cycle.

In Fig. 8, is shown another arrangement of the re-heaters; the coils, 12, through which 105 the steam from the turbine passes, are in this case arranged in one large compartment, 24, superheated steam entering through the pipe, 8, as before and leaving after condensation, by the pipe, 25, after which its course is as 110 described above.

Instead of dividing the superheated steam into two parts according to the methods of Figs. 7 and 9, I may use the following system. Steam from the generator, 2, (see Fig. 10) is 115 led through the pipe, 29, to the superheater, 30; after being superheated in the coils, 31, it passes through the pipe, 32, direct to the re-heaters, 33, which are, in this case, preferably of the type shown in Fig. 8. The 120 steam then returns through the pipe, 34, to the superheater, when it is re-superheated by passing through the coils, 35, 36, after which it goes direct to the turbine by way of the pipe, 37.

In Fig. 11, I have shown yet another method of conducting the superheated steam through the re-heaters. Steam from the generator, 2, passes as before, through the pipe, 29, to the coils, 31, of the superheater, 130

30; it then passes through the pipe, 38, to the reheaters, 39. These are of the same general type as those shown in Fig. 8, except that the coils are divided into upper and 5 lower sets. The steam after passing through the upper coils, 40, 40, of the re-heaters returns through the pipe, 41, to the coils, 35, 10 36, of the superheater and after issuing thence divides into two parts, the one part passing through the pipe, 42, to the turbine and the other part by way of the pipe 43, through 15 the lower coils, 44, 44, of the reheaters, the water of condensation being returned by the pump, 45, to the generator, either directly through the pipe, 46, or indirectly through 20 a feed water heater such as is shown at 26, Fig. 7.

With regard to the turbine itself, as above mentioned, it is of the compound or multiple stage expansion impact type. Each stage of the expansion thus forms a turbine of what is known as the Laval type. Each pair of fixed and moving elements of this turbine also constitutes a complete turbine in which 25 the drop of pressure is arranged to take place in the jets of the fixed element only. The jet chamber of the second stage is supplied through the first re-heater, and here again the drop of pressure takes place in the fixed 30 jets of the second stage, and so on through the various stages of expansion in the turbine down to the exhaust.

It will be seen that by means of the re-heaters provided at each stage of expansion, 35 the temperature of the turbine is maintained practically uniform from end to end and the exhaust steam will pass from the turbine practically at the temperature at which it, at each stage passes, to the re-heater, the larger the number of stages employed, the nearer being the approach to isothermal expansion. The exhaust steam then delivers through a passage, in which is situated the generator for the extraction of 40 its heat and then into the condenser, which is preferably a jet or ejector condenser employing practically air freed water.

It will be seen that various elements of my complete isothermal expansion power generator 45 may be omitted without departing from my invention, although of course, the omission of these elements will involve a less economical production of power. For example:—

(a) The regenerator may be omitted and in this case the isothermal expansion is only carried over a portion of the range the remainder of the expansion being effected adiabatically; reheating should, however, be 55 carried to such a stage as to insure a slightly superheated exhaust. I find it possible to secure a considerable gain in economy by the use of only three reheating stages, the steam from the last of these being preferably ex-

panded adiabatically and passed through the 65 regenerator.

(b) It will be obvious that the air regenerator may be omitted and also the condenser, although such omissions will involve a 70 smaller advantage.

According to one form of turbine (see Fig. 12) I construct the casing of a number of sections, 50 to 57, bolted steam-tight to each other in such a manner as to provide a set of chambers, 58 to 65, in which the turbine-wheels revolve.

Taking the section of casing, 52, as an example for the purposes of description, and referring to Fig. 12, it consists of the following parts: A disk 66, which may be dished as required, is provided at its center with a circular aperture through which the main shaft, 67, of the turbine passes, the steam tightness of the shaft through said aperture being secured by means of suitable packings, 85 contained within the packing casing, 68. The disk, 66, connects at its circumference with the short cylindrical ring of metal, 69, which forms the circumferential wall of the wheel chamber, 60; extending for about two-thirds of the distance round the outside of the ring, 69, in a second partial ring, 70, connected to the inner ring by means of the web or partition, 71; this web, together with that in the adjacent section of the casing and the 90 inner and outer rings, forms a passage 60^a, into which the steam, on its return from a re-heater passes by way of the opening, 60^b, Fig. 8. These steam passages are numbered in the figures to correspond with the wheel 100 chamber to which they pass steam and are distinguished by the suffix "a;" similarly the openings giving access to these passages and to which the connections from the re-heaters lead bear the suffix "b". The web, 71, at several points, 72, is hollowed so as to form ports, 60^c, (extending into the disk 66) through which the steam may pass to the nozzles, the steam to the ports being controlled by piston valves 60^d. The piston 105 valves controlling corresponding ports in the different sections are all mounted on one spindle such as 73 in Fig. 12.

The exhaust from any wheel chamber, for example No. 59, takes place by way of a recess, 59^e, formed in the lower part of the disk portion of the section, 52, of the turbine casing, the steam thus entering the chamber, 59^f, and thence passing through the opening 59^g, to its appropriate re-heater. The same 115 system of suffixes is used for the reference letters as described above.

The last section, 57, is somewhat different in the particular turbine illustrated, since no re-heater is provided between the wheel 125 chambers, 64 and 65; thus the exhaust from the chamber, 64, passes by way of the recess, 64^e, in the disk portion of section, 57, direct

into the passage, 65^a, (which in this case passes completely round the turbine) whence the steam is distributed by means of the valves, 65^d, and ports, 65^c, into the last wheel 65 chamber, 65.

More than one re heater may be omitted if desired and the necessary modifications made in the casing sections concerned in the manner described in the last paragraph.

10 To the high pressure section of the casing, 50 a cover, 75, is secured containing an annular passage, 58^a, to which steam passes through the opening, 58^b, the steam being distributed by way of the valves, 58^d, to the 15 wheel-chamber, 58. The section, 50, is also provided with a stuffing box and gland, 76, through which the shaft, 67, passes to the outside of the turbine. At the low pressure end of the turbine, a cover is provided which 20 forms an exhaust passage, 77, for the steam from the wheel chamber, 65, this cover also supporting a stuffing-box and gland, 78.

Although the sections and covers of the casing have for convenience been described 25 as though formed each of one piece, they are in reality formed in halves, as shown in the end views and bolted together.

The turbine shaft, 67, is supported beyond the ends of the casing in bearings, 79 and 80, 30 preferably provided with a spherical portion, 81, so as to admit of a certain amount of self-adjustment; these bearings are mounted on suitable pedestals, 82, tied together by connecting pieces, 83, the weight of the casing 35 being taken by brackets, 84.

It will be seen that an isothermal expansion turbine of my new type has to work under the maximum temperature of the cycle. This has the disadvantage that 40 lubrication is rendered more difficult. It has however, several great advantages. One of these is that the steam can be maintained practically dry throughout the whole range of expansion. This fact has great influence 45 in reducing the frictional losses in the turbine. Again, no great variations of temperature exist in the turbine, the whole turbine casing being practically maintained at the same temperature. The difficulties or 50 dinarily occurring in steam turbines through unequal expansion due to unequal heating of the different parts of the turbine practically disappear.

Although I have used the term "isothermal expansion" in setting forth my invention I am, nevertheless, aware that the expansion through each stage is actually closely adiabatic. The effect of the re-heaters taken in conjunction with the adiabatic expansion, 55 is, however, to cause the resultant expansion line to cross and re-cross an isothermal line drawn at about the mean temperature of the re-heats, said expansion line thus approximating to such an isothermal line more or

less closely according to the number of re-heats and it is in this sense that I wish the words "isothermal expansion" to be construed, both in the body of the specification and in the following claims.

A form of apparatus for carrying out the 70 process claimed herein, is made the subject of another application by me, Serial Number 249253, dated March 9/05.

Having now described my invention, what I claim as new and desire to secure by Letters 75 Patent is:—

1. In elastic fluid turbines, the method of obtaining increased economy in working consisting in expanding the fluid in a series of stages and reheating between stages so as 80 to render the expansion approximately isothermal.

2. In elastic fluid turbines the method of obtaining increased economy in working consisting in superheating the fluid and expanding said fluid in a series of stages and reheating between stages so as to render the 85 expansion approximately isothermal.

3. In elastic fluid turbines the method of obtaining increased economy in working 90 consisting in expanding the fluid in a series of stages; reheating between stages so as to render the expansion approximately isothermal and passing the exhaust fluid through a regenerator so as to restore heat to the working 95 fluid.

4. In elastic fluid turbines the method of obtaining increased economy in working consisting in superheating the fluid; expanding said fluid in a series of stages and reheating between stages so as to render the expansion approximately isothermal and passing the exhaust fluid through a regenerator so as to restore heat to the working fluid.

5. In elastic fluid turbines, the method of obtaining increased economy in working consisting in expanding the fluid in a series of stages and reheating to the initial temperature between said stages, thereby rendering the expansion approximately isothermal. 110

6. In elastic fluid turbines, the method of obtaining increased economy in working consisting in superheating the fluid; expanding said fluid in a series of stages and reheating to the initial temperature of superheat between said stages, thereby rendering the expansion approximately isothermal. 115

7. In elastic fluid turbines, the method of obtaining increased economy in working consisting in expanding the fluid in a series of stages and reheating between stages, the mean temperatures of the re-heats being substantially identical.

8. In elastic fluid turbines, the method of obtaining increased economy in working consisting in superheating the fluid; expanding said fluid in a series of stages and reheating between stages, the fluid being superheated

throughout its expansion and the mean temperatures of the re-heats being substantially identical.

9. In elastic fluid turbines, the method of obtaining increased economy in working consisting in superheating the fluid at a point of the cycle, expanding said fluid after said superheating in a series of stages to such an extent only at each stage as to keep it dry, re-heating between stages, the mean tempera-

tures of the re-heats being substantially identical and passing the exhaust fluid through a regenerator so as to restore heat to the working fluid.

In witness whereof I have hereunto set my hand in presence of two witnesses.

SEBASTIAN ZIANI DE FERRANTI.
